BRASSIÈRE AND GARTER BELT

Nancy Gradara, White Plains, N. Y.

Application December 21, 1946, Serial No. 717,779

2 Claims. (Cl. 2—42)

1

This invention relates to improvements in brassières and particularly to a combination brassière and hose supporter.

Broadly, it is an object of my invention to provide a brassière with elastic hose supporters arranged so that the parts of the body are not restricted in their movements nor will constriction or binding take place at any part, especially the stomach, making it exceptionally comfortable and desirable for pregnant women.

A further object is to provide a combined brassière and hose support which is practical, ornamental, attractive, comfortable and comparatively inexpensive and which can be worn underneath a large variety of outergarments. A further object is to provide a combined undergarment described above which is also light and cool and fully perform the necessary desired functions.

With the foregoing and other objects in view, reference is had to the following detailed description in connection with the accompanying drawings, in which:

Figure 1 is a side view of the brassière and hose support in position upon the body of a woman.

Figure 2 is a front view thereof, and

Figure 3 is a front plan view thereof.

Referring to the drawings, numeral 10 represents a brassière body preferably made of non-stretchable material and fashioned to conform to the contour of the bust by providing a seam 11 running along the center of each bust to the nipple point. The two bust portions are joined in the centre by seam 12 and the lower portions of both busts are reinforced by a superimposed fabric 13 on the inside as shown in the drawings which is stitched along dotted stitch lines 14. Side and back portions 15 are attached by stitching 16 at the sides. The top edge, bottom edge and side seams are reinforced by stitched ribbons. The lower part of the entire brassière has attached thereto an elastic member 17 which causes the lower part of the brassière to hug the body. At one end there is a hook 18 and at the opposite end several eyes 19 for adjustability. A pair of shoulder straps 20 are attached at one end to the upper center of the bust portion and at the opposite end to the upper end of the side and back portions 15.

Attached to the lower central part of the brassière are a pair of crossed elastic members 21 running diagonally across the front towards the sides. Attached to each of the lower extreme ends of the side and back members 15 is a diag-

2

onal elastic member 22 which crosses the diagonal member 21 at the upper part of the thigh as shown at 23. Elastic members 21 and 22 have hose clasps 24 attached to each end. The members 21 are crossed almost at the point of attachment 25 at the center of the brassière and run diagonally so that they do not constrict the expansion and contraction of the stomach. Crossing the elastics at 23 at the upper part of the thigh is the point of least movement of the limbs so that the maximum amount of freedom is permitted without constriction. Furthermore, running the elastic members 21 and 22 diagonally follows the direction of the ligaments so that the muscles are aided in their movements.

It is obvious that various changes and modifications may be made in the details of construction and arrangement of parts without departing from the general spirit of the invention.

20 I claim:

1. A ladies garment of the character described comprising in combination a brassière portion, a body encircling member attached to said brassière portion, means for fastening said body encircling member at its ends, shoulder straps connected to the upper part of said brassière portion and said body encircling member with two front elastic supporter members connected to the lower central part of said brassière portion, said elastic members crossing and attached to each other adjacent said central lower brassière portion and two rear elastic supporter members attached to the rear ends of said body encircling member, said front and rear supporter members crossing one another and attached to each other at such crossing portions at a short distance from their ends opposite said attached ends and hose clasps at each end of said front and rear elastic supporter members.

2. A ladies' garment of the character described comprising in combination a brassière portion, a body encircling member attached to said brassière portion, the ends of said body encircling member meeting at the back of the wearer, means for fastening said body encircling member at its ends, shoulder straps connected to the upper part of said brassière portion and said body encircling member with two front elastic supporter members connected to the lower central part of said brassière portion, said elastic members crossing and attached to each other at the central upper part of the stomach of the wearer and two rear elastic supporter members attached to the rear ends of said body encircling member, said front and rear supporter members crossing one another

and attached to each other at the point where said front and rear supporter members cross one another, said crossing point of said front and rear supporter members being approximately at the central side upper thighs of the wearer and hose clasps at each end of said front and rear elastic supporter members.

NANCY GRADARA.
